UNITED STATES PATENT OFFICE.

NATHAN R. GOODWIN, OF TRENTON, NEW JERSEY.

ATTACHMENT FOR CALENDERS.

Application filed February 7, 1923. Serial No. 617,527.

- This invention relates to an attachment for calenders which sheet the rubber compound in a tire manufacturing plant, and has for an object to provide an apparatus which will receive the calendered rubber in strips of varying widths and automatically laminate the same into a composite strip adapted to be severed into suitable lengths and employed as treads for tires.
- Another object consists in providing means for suitably adjusting the apparatus in cooperative relationship with a calender.
- Another object consists in providing means for guiding the strips of calendered rubber into exactly proper relationship for superposition, one upon the other.
- A further object consists in providing certain improvements in the form, construction and arrangement of the several parts, whereby the above named and other objects may be effectively attained.
- A practical embodiment of the invention is represented in the accompanying drawings, in which
- Fig. 1 represents a front view of the apparatus.
- Fig. 2 represents a side view thereof, on an enlarged scale, and showing, diagrammatically, the relationship of the device with respect to the calender.
- Fig. 3 represents a detail plan view, on a still larger scale, of part of the guiding mechanism.
- Fig. 4 represents a side view of the same, partly in section.
- Fig. 5 represents a section taken in the plane of the line V—V of Fig. 3, looking in the direction of the arrows.
- Fig. 6 represents a section taken in the plane of the line VI—VI of Fig. 4, looking in the direction of the arrows.
- Fig. 7 represents a greatly enlarged diagrammatic view of the laminated tread which is the product of the apparatus.
- The calender may be of any well known and approved form, and is represented somewhat diagrammatically in Fig. 2, where its framework is marked 1 and its rolls 2, 3 and 4.
- The rubber compound being fed to the calender is indicated by 5 and the usual knives 6 for slitting the calendered sheet into strips of suitable width are shown as pivoted at 7 on a suitable support 8.
- On each side of the framework 1, there is
- a vertically disposed channel-iron member 9 which has its side walls provided with a series of perforations 10 adapted to receive pins 11 in different vertical adjustments. These pins 11 serve to support rods 12 and 13 which extend from side to side of the framework 1 with their ends entering the channel-iron members 9 and resting upon the pins 11 in whatever position the latter may be set. The rod 12 has a block 14 at each end thereof in order to provide suitable bearings therefor.
- Normally, the rod 12 is mounted about opposite the central roll 3 of the calender, and it carries a swinging frame that consists of side members 15, 16, rolls 17, 18 and a tie rod 19. The side members 15, 16 are secured to head pieces 20 that embrace the rod 12 and may be fixed in predetermined position by set screws 21. The head pieces 20 also carry a cross bar 22.
- On the rod 12 is mounted a series of yokes 23, ten being employed in the present instance, and each of these yokes carries a roll 24 and a guide rod 25, the roll 24 being mounted on a stub shaft 26. Each roll is hollow, as clearly shown in Fig. 5, and provided at each end with a ball bearing 27, the said bearings being mounted upon a reduced portion of the shaft 26 which enables the bearings to be confined between a shoulder 28 and a collar 29, the former resulting from the reduction in size of the shaft 26, and the latter being fixed in place on the end of the shaft 26 by a pin 30.
- The yokes 23 are suitably adjusted and fixed against movement longitudinally with respect to the rod 12 by collars 31 and set screws 32.
- Each guide rod 25 carries a pair of guide pieces 33 that embrace the rod and are secured in the desired position thereon by set screws 34, which are threaded into the pieces 33 and have their inner ends adapted to bear against the rod 25.
- A bifurcated bracket 35 is mounted in a support 36 which embraces the rod 12 at a point outside of but adjacent to the side member 16, the said support being fixed against turning movement on the rod 12 by a bolt 37, so as to hold the bracket in upright position.
- A roll 38 is mounted on a shaft 39 which is carried in the ends of the bracket 35, as clearly shown in Fig. 2, the said roll being

preferably hollow and provided with ball bearings as shown and described in connection with the roll 24.

Another roll 40 is carried, through the medium of similar ball bearings, on a stub shaft 41 that is mounted for swinging adjustment about a pivot 42 in a support 43 adjustably fixed on the side member 16 by a set screw 44.

10 It is desirable, at all times, to keep the rolls 24 and 38 parallel with each other and, for this purpose, the inner ends of the shafts 26 which carry the rolls 24 are threaded, as clearly shown at 45 in Fig. 5, into the yokes 15 23 with their ends adapted to project rearwardly of the latter and abut the cross bar 22. The pins 30 serve as a manual grip for turning the shafts 26 and it will be seen that, by this means, the yokes 23 can be 20 slightly turned on the rod 12 so as to provide the necessary adjustment.

As previously indicated, the rod 12 serves as a pivot for the frame 15, 16, 17, 18, 19 and the latter, of course, will tend, under 25 the force of gravity, to fall into parallelism with respect to the channel-iron members 9. This tendency is resisted by the rod 13 against which the side members 15, 16 of the frame normally rest. By raising or 30 lowering the position of the rod 13 in the channel-iron members 9, the said frame may be caused to rest in a greater or less angular position with respect to the said channel-iron members, and thereby to bring its roll 35 17 nearer to or further away from the lower roll 2 of the calender.

I prefer to have the rolls 17 and 18 both hollowed and mounted on ball bearings, as in the case of rolls 24.

40 In operation, the compound rubber material 5 is fed in between the rolls 3 and 4 of the calender in the customary manner. The action of these rolls, which are driven, serves to sheet the material, and it is slit 45 into strips by the knives 6 as it passes around the rear of the roll 3. The strips are then led between the rolls 3 and 2, and given an additional compression. From the roll 2, the strips pass around the roll 17 and thence upwardly to the rolls 24 that lie 50 at right angles to the roll 17. It will be observed that the strips are all of different widths, except the last two at the right in Fig. 1, and that the strips lie edge to edge 55 and in the same plane as they pass around the roll 17. When, however, the strips engage the rolls 24, they all have their flat sides toward each other and lie in different planes so that, as they pass up onto the roll 60 38, they are laid one upon the other, the wide strips being underneath and the superposed strips graduating in width to the top, as clearly shown in Fig. 7. The guide pieces 65 33 are so adjusted on the rods 25 as to have all except the two narrowest strips laid upon

each other with their centers coinciding. The two narrowest strips are guided onto the next widest strips so as to lie edge to edge, with an interval between, as is also clearly indicated in Fig. 7. This laminated 70 form, with the strips becoming narrower from the bottom toward the top, provides a tread which is adapted to assume substantially a crescent shape in cross section after it has been applied to the tire and acted 75 upon by the mold, while the placing of the two narrow strips on top is a particular arrangement to especially adapt the tread for receiving a suitable non-skid design.

As the strips pass over the roll 38, they 80 are compacted together, and this action is repeated when the combined strips travel around the roll 40 which lies at right angles to the roll 38. From the roll 40, the combined strips are carried along under the roll 85 2 of the calender and onto a suitable conveyer belt 46 that travels around a pulley 47 and other suitable pulleys, not shown. This conveyer belt leads the combined strip to a suitable delivery table, or the like, 90 where it may be severed into the desired lengths. For certain operations and in connection with certain calenders, it is desirable to have the roll 17 nearer to or further away 95 from the calender, and this may be accomplished by adjusting the rod 13, as hereinabove described. It may also be deemed advantageous, in some instances, to employ a roll located at a lower point than the roll 17, for receiving the strips from the calender 100 and, to this end, the roll 18 is provided, which is similar in all respects to roll 17. The adjustment of the roll 40 on the side member 16 also enables it to be brought into such a position that the completed strip 105 will pass in suitable engagement with the roll 2 of the calender while on its way to the conveyer belt 46.

As a result of this invention, instead of receiving strips from the calender, which 110 have to be manually laid one upon the other in order to form the tread material, the complete tread strip itself is automatically produced and delivered, so that the only manual operation employed is to cut the 115 same to proper lengths.

It will be understood that various changes may be resorted to in the form, construction and arrangement of the several parts without departing from the spirit and scope of 120 my invention; and hence, I do not intend to be limited to the details herein shown and described, except as the same may be included in the claims.

What I claim is:

1. An attachment for calenders comprising, a freely rotatable roll for receiving tread strips from a calender, another freely rotatable roll for superposing such strips upon each other and compacting them with- 130

out otherwise applied pressure, said rolls being actuated by the movement of the strips in contact therewith, and means for delivering said superposed strips to a desired point, 5 said delivering means serving to pull upon the strips for causing them to actuate the rolls.

2. An apparatus of the character described comprising, means for receiving tread strips 10 from a calender and superposing the same upon each other, said means including a frame, a roll in the frame fitted to receive the strips coming from the calender in edge to edge arrangement, a set of rolls fitted to 15 receive the strips and turn them into position with their centers substantially in line, a roll fitted to receive the strips in superposed condition, and means for adjusting said set of rolls so as to keep them in parallelism with said last named roll.

3. An apparatus of the character described comprising, means for receiving tread strips from a calender and superposing the same upon each other, said means comprising a 25 rod, a swinging framework mounted on the rod, a roll carried in the framework fitted to receive the strips coming from the calender in edge to edge arrangement, a set of rolls mounted on said rod fitted to receive the strips and turn them into position with their centers substantially in line, a roll mounted on said 30 rod fitted to receive the strips in superposed condition, a roll mounted on said frame fitted to receive and compact the combined strips, and means for conveying the combined strips away from the last named roll.

4. An apparatus of the character described

comprising, means for receiving tread strips 35 from a calender and superposing the same upon each other, said means comprising a rod, a swinging framework mounted on the rod, a roll carried in the framework fitted to receive the strips coming from the calender in edge to edge arrangement, a set of rolls mounted on said rod fitted to receive the strips and turn them into position with their centers substantially in line, a roll mounted on said rod fitted to receive the strips in superposed condition, and a roll mounted on said frame fitted to receive and compact the combined strips.

5. An apparatus of the character described comprising, means for receiving tread strips 50 from a calender and superposing the same upon each other, said means comprising a rod, a swinging framework mounted on the rod, a roll carried in the framework fitted to receive the strips coming from the calender in edge to edge arrangement, a set of rolls mounted on said rod fitted to receive the strips and turn them into position with their centers substantially in line, a roll mounted on said rod fitted to receive the strips in superposed 55 condition, a roll mounted on said frame fitted to receive and compact the combined strips, and means for conveying the combined strips away from the last named roll.

In testimony, that I claim the foregoing 60 as my sole invention, I have signed my name this fifth day of February, 1923.

NATHAN R. GOODWIN.
